UNITED STATES PATENT OFFICE.

EMIL KASELOWSKY, KARL GRAMM, AND GUSTAV KÜRBITZ, OF BERLIN,
GERMANY, ASSIGNORS TO FRIEDRICH KARL GLASER, OF SAME PLACE.

VALVE-GEAR FOR MULTIPLE-CYLINDER ENGINES.

SPECIFICATION forming part of Letters Patent No. 408,915, dated August 13, 1889.

Application filed October 22, 1888. Serial No. 288,732. (No model.)

To all whom it may concern:

Be it known that we, EMIL KASELOWSKY and KARL GRAMM, both subjects of the King of Prussia, and GUSTAV KÜRBITZ, a subject 5 of the Duke of Sachsen-Heiningen, residing at Berlin, in the Kingdom of Prussia, Germany, have invented new and useful Improvements in Valve-Gears for Three and Multiple Cylinder Engines, of which the following is a 10 specification.

The herein-described valve arrangement for three-cylinder engines or for multiple-cylinder engines has for its object to effect the supply and discharge of the steam or other 15 working fluid by means of double piston-valves, which are quite free from pressure and are worked from a single inclosed eccentric carrying several eccentric-rings independent from each other and made each in one 20 piece, each ring serving to operate only one piston-slide. This arrangement avoids the disadvantages attending the various arrangements of valve-gear hitherto adopted—as, for instance, when oscillating slide-valves or 25 cocks are employed subject to rapid to-and-fro movements, which cause wear, looseness, and leakage, as well as irregularity in the distribution of the working-fluid. Especial advantage of the improved valve-gear lies in 30 the perfect relief of the valves from pressure in any direction, and in the circular fitting by which one-sided or inexact working of the parts is entirely avoided. Moreover, in the improved construction the exhaust is regulated by means of an auxiliary slide worked 35 from the same eccentric-rod as the main slide, instead of employing, as in engines hitherto known, some special valve-cock or other arrangement for the purpose. Independently 40 of the novel valve-gear there is provided, according to this invention, for rapidly-moving engines a separate exhaust by a special passage through each piston, which is thus made to operate as an exhaust-valve opening at the 45 end of the expansion period of the stroke.

The accompanying drawings show part of a three-cylinder engine arranged according to this invention, Figures 1 and 2 representing partial sections on planes at right angles 50 to each other through the axes of the slide-valves.

Similar letters of reference indicate corresponding parts in both views.

a is the eccentric-sheave fixed on the crank-shaft and surrounded by the three separate 55 rings *b*, *c*, and *d*, to which are secured the eccentric-rods *b'* *c'* *d'*. The ring *b* occupies the whole breadth of the sheave, while the rings *c* and *d*, arranged one near the other, surround the ring *b*. 60

At the side of each cylinder is fitted the outer piston-slide *b²*, having within it the auxiliary slide *b³*, both worked from the eccentric-rod *b'*, the outer *b²* directly and the inner *b³* by a rod *b⁴* from a bracket *b⁵*, projecting at the side of the rod *b'*. In like manner the slide-valves of the other cylinders are worked, respectively, from the rods *c'* *d'*. 65

The working-fluid is supplied by the pipe *e* to the annular space *f*, surrounding the smaller 70 part of the slide. The exhaust passes through the ports *g* and the tubular interior of the auxiliary slide *b³*. To let escape the gases, besides the piston-slide *b²* and the auxiliary slide *b³*, the hereinafter-described construction 75 may also be employed. In the working piston *B* are formed two opposite passages *h*, which are arranged in such a manner that at the forward stroke of the piston during the filling and expansion period the exhaust-port 80 remains closed; but toward the end of the stroke open to the central cavity of the engine, so that by these, as well as by the slide-valve, there is free passage for exhaust. During the return-stroke of the piston the passages *h* are again closed. 85

Having thus described our invention, what we claim, and desire to secure by Letters Patent, is—

1. In a valve-gear for multiple-cylinder engines, the combination, with the single eccentric *a*, the separate eccentric-rings *b* *c* *d*, mounted on the eccentric and provided with the rods *b'* *c'* *d'*, having brackets *b⁵* *c⁵* *d⁵*, the distributing-piston slide-valves *b²* *c²* *d²*, connected to the rods *b'* *c'* *d'*, the auxiliary slides *b³* *c³* *d³*, and the rods *b⁴* *c⁴* *d⁴*, connected to the auxiliary slides and to the brackets, substantially as described. 90

2. In a valve-gear for multiple-cylinder engines, the eccentric *a*, eccentric-rings *b* *c* *d*, provided with the rods *b'* *c'* *d'*, having brackets 100

*b*⁵ *c*⁵ *d*⁵, the piston slide-valves *b*² *c*² *d*², connected to the rods *b*' *c*' *d*', the auxiliary slides *b*³ *c*³ *d*³, and the rods *b*⁴ *c*⁴ *d*⁴, connected to the auxiliary slides and to the brackets, in combination with the working-piston B, provided with the exhaust-passage *k*, substantially as described, whereby a second exhaust of the working-fluid will automatically take place at the end of the stroke, as set forth.

In testimony whereof we have signed our names to this specification in the presence of two subscribing witnesses.

EMIL KASELOWSKY.
KARL GRAMM.
GUSTAV KÜRBITZ.
